UNITED STATES PATENT OFFICE.

CHARLES BURRESS TURNER, OF WHITE SULPHUR SPRINGS, WEST VIRGINIA.

SICKLE-BAR.

SPECIFICATION forming part of Letters Patent No. 392,833, dated November 13, 1888.

Application filed May 2, 1888. Serial No. 272,583. (No model.)

To all whom it may concern:

Be it known that I, CHARLES BURRESS TURNER, a citizen of the United States, residing at White Sulphur Springs, in the county 5 of Greenbrier and State of West Virginia, have invented new and useful Improvements in Sickle-Bars, of which the following is a specification.

The invention relates to improvements in 10 cutter-bars for harvesting-machines; and it consists in the construction and novel combination of parts hereinafter described, illustrated in the accompanying drawings, and pointed out in the appended claim.

15 Figure 1 of the drawings represents a perspective view of a portion of a cutter-bar embodying the invention. Fig. 2 is a perspective view of the keeper-bar detached. Fig. 3 is a perspective view of one of the triangular knives detached, showing the under side 20 thereof. Fig. 4 is a perspective view of one end of the knife-bar, showing the rear side thereof and a knife. Fig. 5 is a transverse section of the knife-bar and the keeper-bar on 25 line $x-x$ of Fig. 1. Fig. 6 is a sectional view on line $y-y$ of Fig. 1, and Fig. 7 is a detail perspective view of a portion of the knife-bar detached.

Referring to the drawings by letter, A designates the cutter-bar, of usual shape and attached in the usual manner to the machine to be reciprocated therefrom. The cutter-bar has in its rear side a deep longitudinal recess, a , which has a rectangular enlargement, a' , at 30 the inner end of the cutter-bar. The said enlargement is open at the top, rear, and inner end and forms the upper and lower shoulders a^2 a^3 , near the inner end of the cutter-bar, and the recess a opens upon the rear edge of the 35 cutter-bar. The recess extends slightly beyond the knives, but has its outer end closed.

40 B are transverse notches in the upper surface of the knife-bar. The sides of these notches are dovetailed. The bottoms of the 45 said notches are flush with the top of the recess a . These notches are formed to receive the rectangular-shaped butts of the detachable knives, hereinafter described.

45 b is a longitudinal groove in the roof of the recess a and extending the entire length of said roof, and C C are knives of the usual triangular shape, provided with the rectangular

butts c , dovetailed on the side edges, which fit within the notches B, and are each provided in its under surface with the transverse 55 groove c' , that registers with and completes the groove b when the knives are in place, so that a continuous groove, $b c'$, is formed thereby.

D is the keeper-bar, fitting and sliding in the recess a , and provided on its upper surface with a longitudinal rib, d , that enters and fits in the groove $b c'$ and locks the knives in place. The said knives are thus locked vertically by the dovetailed grooves B and longitudinally by the continuous groove $b c'$ and 60 the rib d . The keeper-bar has at its inner end the rectangular head E, provided with the shoulders e adjacent to the rib d , which rest against the shoulders a^2 when the keeper-bar is in place and prevent the latter from being 65 pushed in too far; and in order to more effectually hold the keeper-bar in its proper position I provide it with a longitudinal rib, d' , on its under side, which engages a groove, h , in the base of the recess a , the said groove having 70 its floor flush with the base of the enlargement a' . 75

F is a retaining-bar in the rectangular enlargement a' of the recess a , and having a vertical shoulder, f , on its rear face, that is adapted 80 to engage a shoulder, e' , on the inner face of the rectangular head E of the keeper-bar, thereby retaining the latter in place against withdrawal. G is a coiled spring seated in the enlargement a' in front of the retaining-bar 85 and forcing the same into engagement with the keeper-bar, so that the shoulder f will engage the shoulder e' . The parts are thus firmly bound together and operate as effectively as a solid knife-bar upon which the knives or blades 90 are bolted, and by withdrawing the keeper-bar either wholly or partially all of the knives, or any number of them, can be readily withdrawn for repairs or sharpening, as will be readily understood. 95

Having described my invention, I claim—

The combination, with the longitudinally recessed cutter-bar having transverse dovetailed notches in its upper side and provided with an enlargement, a' , of the knives having the rectangular butts, with transverse grooves on their under sides and dovetailed on their edges and fitting in the transverse dovetailed notches of the cutter-bar, the sliding keeper-

bar having the head E, provided with the shoulder e', the retaining-bar F, seated in said enlargement and having the shoulder f to engage the shoulder e', and the spring G, bearing on the bar F to hold said shoulders in engagement, substantially as specified.

In testimony that I claim the foregoing as my

own I have hereto affixed my signature in presence of two witnesses.

CHAS. BURRESS TURNER.
